UNITED STATES PATENT OFFICE.

MORTON L. JOHNSON, OF CHICAGO, ILLINOIS, ASSIGNOR TO CORWIN TELEPHONE MANUFACTURING COMPANY, OF CHICAGO, ILLINOIS, A CORPORATION OF ILLINOIS.

TELEPHONY.

1,075,260.

Specification of Letters Patent.

Patented Oct. 7, 1913.

Application filed August 10, 1911, Serial No. 643,341. Renewed July 25, 1913. Serial No. 781,255.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems and has for one of its objects the provision of means whereby the stations upon a party line that extends to an exchange may have telephonic communication to the exclusion of the exchange and mechanism controlled at one of the party line stations that serves to prevent the telephone at the remaining party line station from becoming connected with the party line when telephonic connection is established between the first party line station and said party line.

My invention has for its further object the provision of means whereby apparatus at an exchange, which is automatically responsive to circuit changes at substations, may be held in a condition of use during the time telephonic communication is established between the party line stations to the exclusion of the exchange, there being means for removing the influence of the aforesaid means to permit the party line station that appropriates the party line to have operating influence over the exchange equipment.

I will explain my invention more fully by reference to the accompanying drawing showing the preferred embodiment thereof and which diagrammatically illustrates two telephone lines extending to an exchange, one of these telephone lines extending to two party line stations.

The drawing illustrates a telephone exchange at A, a single line subscriber's station at B and party line subscribers' stations at C, D. The telephone line extending from station B has metallic sides which terminate in a tip line spring 1 and a sleeve line spring 2 of a spring jack 3. The telephone line extending from the party line stations C, D has its sides terminate in a tip line spring 4 and a sleeve line spring 5 of a spring jack 6, the spring jacks 3 and 6 being located at the same exchange A. The

equipment at the exchange A may be of any well known or suitable type and therefore does not require description in detail. The drawing shows one of a number of manually controlled link circuits, the link circuit 60 shown including a calling plug 7 and an answering plug 8, this link circuit and its companions being adapted to connect the station B with the line having the party line stations C and D, the plugs being inserted 65 in the jacks of the respective lines for this purpose.

There are features of my present invention that are not only of service in connection with manual exchanges but are also of 70 service in connection with those exchanges in which lines are automatically extended. To the extent that the features of my present invention are of service in connection with both general classes of systems, I 75 generically claim the invention herein disclosed. My copending application Serial No. 643,342, filed August 10, 1911 relates more particularly to systems in which lines are automatically extended.

In the embodiment of the invention illustrated, each line is provided with a cutoff relay 9, a line relay 10 and a visual signal 11 governed by the line relay, these parts being governed by the equipment at the exchange and substations in a manner so well understood as to require no description. My invention more directly concerns the relationship of the party line stations with each other and also with the exchange and I 80 will describe the equipment illustrated at each party line station, similar characters of reference being given to similar parts at both the party line stations as the equipments at these stations are identical in construction, circuit arrangement and function, in the embodiment of the invention shown. The party line stations C, D may be located at different premises, or they may be located at the same premise, in which latter 100 case either of the stations may constitute an attendant's station and the other the principal station. If the stations are collocated, but one signal receiving bell may be employed upon the premises where they are located, but if the stations are widely separated each station should be equipped with such a bell. I have shown a signal receiving bell 12 in bridge of the party line at each of the stations C, D. When two bells are 110

employed the operator at the exchange A may select one or the other for operation, if desired, or both bells may be caused to respond, the party at either station being 5 privileged to respond and it may be arranged to have one of the parties respond if the bell at his station rings for an unusual length of time, it then being understood that it is the object to have the other party 10 respond when his bell rings at all.

Each station is provided with a telephone receiver switch hook 13 adapted, when relieved of the weight of the telephone receiver 14, to connect the telephone receiver 15 and transmitter 16 in a circuit path between the switch springs 17 and 18. Each switch hook is provided with a post 19 that is depressed when the associate receiver is upon its switch hook, the limit to which such post 15 20 25 30 35 40 45 50 55 60 65 70 75 80 85 90 95 100 105 110 115 120 125 130

18 may be depressed being determined by a stop 19. The post 18 is provided with a lug 20 that engages the spring 17 and the springs 17 and 16 are mechanically united by a strut 21 of insulating material. By this arrangement the receiver, when placed upon its switch hook, is adapted to bring the springs 16 and 17 into engagement with their normal contacts, and, when the springs 16 and 17 are otherwise free to move, said 30 springs will by their own resilience separate from their normal contacts and engage their alternate contacts. The mechanically united springs 16 and 17 are provided with a common extension 22 that normally lies beneath the catch 23 carried by the armature of a magnet 24, this catch serving to prevent the springs 16 and 17 from engaging their alternate contacts. The lug 20 normally overcomes the resilience of the springs 16 and 17 35 40 45 50 55 60 65 70 75 80 85 90 95 100 105 110 115 120 125 130

40 for the purpose of maintaining them in engagement with their normal contacts, a slight clearance intervening between the extension 22 and the catch 23 that will permit the post 18 to rise sufficiently, when the catch 23 is in normal position, to effect engagement between the associate switch hook and the contact located above the same, such movement however being sufficiently restricted by the catch 23, when in normal position, to prevent the springs 16 and 17 from leaving their normal contacts and engaging their alternate contacts when the associate telephone receiver is removed from its switch hook. The manually operated switch 55 60 65 70 75 80 85 90 95 100 105 110 115 120 125 130

26 controls a gap in the bridge between the sides of the party line, which bridge includes the magnet 24 that is desirably of high resistance say 1,000 ohms. A party line subscriber, in initiating a call for a line 60 65 70 75 80 85 90 95 100 105 110 115 120 125 130

terminating at the exchange A will remove his telephone from its switch hook and will also close the contacts at the switch 26 so as to include the magnet 24 in bridge of the party line to cause said magnet to be supplied with current from the common bat-

tery at the exchange whereby the catch 23 is withdrawn from engagement with the extension 22 so that the springs 16 and 17 may break connection with their normal contacts and make connection with the alternate contacts with the result that the telephone receiver and transmitter at the calling party line station are included in bridge of the party telephone line by way of the springs 16 and 17 and their alternate contacts, these alternate contacts being connected with different sides of the party line. A signal is displayed at the exchange in the usual way and the wants of the calling party line stations are attended to in a manner well known. If either of the party line stations is a called station, the bell 12 at such called station will be caused to ring by the operator at the exchange and the answering party line subscriber will repeat the operations which have just been described, thereby placing the telephone receiver and transmitter at such answering party line station in bridge of the party line. If the telephone receiver and transmitter at one of the party line stations is in bridge of the party line, the other party line station cannot become connected with the party line since the low resistance bridge established through said telephone receiver and transmitter will shunt the magnet 24 of the station seeking the line so that the contact springs 16 and 17 at such seeking station will not be free to engage their alternate contacts as a consequence of which the telephone receiver and transmitter at the seeking station are locked out of circuit with the party line. The fact that the line is busy is indicated to the seeking party line subscriber by the failure of the plunger 27 to rise above the plate 28, the extension 22 forcing this plunger above the plate 28 only when the magnet 24 responds, this magnet 24 responding only when the party line is free for appropriation.

In order to enable the subscribers at the party line stations to communicate directly with each other I preferably employ a distinct line between these stations that forms no part of the main party line, though I do not wish to be limited to this arrangement. This distinct line between the party line stations includes a conductor 29 that joins the normal contacts of the springs 17 and a conductor 30 that joins the normal contacts of the springs 16. A battery 31 is included in one of these conductors for the purpose of supplying battery current to the telephones at the party line stations. When either party line station desires to communicate with the other the contacts of a switch 32 are closed by the calling party to include a signal receiver 33 of the called party in circuit, the circuit for such a signal receiver being traceable from the battery 31 through the 110 115 120 125 130

signal receiver 33 at the called station, the contacts of the switch 32 at the calling station back to the battery 31 by way of a portion of the conductor 29 that includes said battery.

When the party line subscribers are to talk with each other the switches 26 at the party line stations are allowed to remain normal and the parties place themselves in direct telephonic communication by way of the conductors 29 and 30 merely by removing the telephone receivers from their switch hooks, the telephone circuit between the stations including the conductors 29 and 30, the switch springs 16 and 17 and the normal contacts of said switch springs. During the conversation between the party line subscribers, the springs 16 and 17 are held out of engagement with their alternate contacts by means of the catches 23 so that the party line proper, which extends to the exchange, is maintained out of telephonic relation with the telephone at both of the party line stations during the establishment of telephonic connection between these stations by way of the conductors 29 and 30, the signal receivers 12 being then amply free to receive incoming signals, while at the same time the line signal 11 at the exchange is not disturbed by any low resistance shunt at the party line stations. In this way telephonic communication may be held directly between the party line stations independently of the exchange so that this conversation may not be listened into by way of any line entering the exchange or by the operator at the exchange. Now let it be assumed that the stations C, D are located in the same place and that one of these stations, say station C, is presided over by an attendant whose duty it is to assist the party at the remaining station in governing the connection of the telephone at such remaining station with the party line. As the system is organized the party at either of the stations is adapted to assist the other in the way described but for the sake of illustration the station C has been selected as the attendant station, it being understood that I do not limit myself to the equipment whereby each of the party line stations may supplement the other in effecting telephonic association with the party line. If the party at station D desires to call another party, say the party at station B, and wishes the attendant at station C to attend to the details of the call, the party at station D will operate the signal 33 at station C and have telephonic communication with the party at station C in the manner which has been described, whereafter the party at station D will restore his telephone to its switch hook to await the signal to be conveyed by his signal device 33 when the called line has been secured. The attendant at station C

will remove his telephone from its switch hook and will operate the switch 26 so as to permit the springs 16 and 17 to engage their alternate contacts, in the manner which has been described, thereby to include the associate telephone receiver and transmitter in bridge of the party line to occasion the operation of the line signal 11 at the exchange. The operator at the exchange will communicate with the party at station C to ascertain the number of the line called for and will connect the spring jack 6 of the calling party line with the spring jack 3 of the called line by the link connector that includes the plugs 7 and 8, the plug 8 then being inserted in the jack 6 and the plug 7 in the jack 3. When the called party at station B responds the party at station C will inform the called party that the party at station D desires to communicate with him whereafter the attendant at station C will close the contacts of his switch 34 to include a magnet 35 in bridge of the party line, this magnet serving to close the contacts of a switch 36 that is in parallel with the switch 34 so that the bridge through the magnet 35 may be maintained at 36 when the contacts of the switch 34 are separated. The bridge established through the magnet 35, this magnet being desirably of high resistance say of 1,000 ohms, affords the passage of sufficient current from the common battery of the common battery exchange A through the supervisory relay 37 at the exchange to maintain this supervisory relay in its energized condition. When the attendant's switch 34 is operated the telephone receiver and transmitter at the attendant's station either has its circuit opened at its switch hook or is limited to circuit relation with the conductors 29 and 30. When the attendant operates the switch 34 his receiver should be free of its switch hook and this receiver is restored to its switch hook while the switch 34 is closed in order to preserve the control of the bridge to be established by the relay 35. In the operations that are being traced the called party B has heard such response, this attendant thereupon informing the party at station D that the called party at station B has responded, this information being secretly conveyed from the attendant's station C to the station D through the agencies and in the manner which has been described. The calling party at station D thereupon closes the contacts of his switch 26 and removes his telephone from its switch hook whereby this telephone becomes connected in bridge of the party line with the result that the bridge established at the magnet 35 is broken and the supervisory signal 37 at the exchange is placed directly within the control of the calling party at station D. The magnet 35 may be equipped with a signal attachment 133

35¹ to inform the operator at the attendant party line station, which ever station this may be, when the other party line station has taken the party line.

5 It will be observed that the party at the attendant station cannot listen in upon the connection that is now established between the calling station D and the called station B since the magnet 24 at the attendant station is shunted by the telephone receiver bridge at the station D, the catch 23 of the shunted magnet 24 preventing the springs 16 and 17 from leaving their normal and engaging their alternate contacts, which 10 latter contacts have to be engaged by these springs in order to enable the attendant at station C to bridge the telephone at this station across the party line which is now connected with the receiver and transmitter 15 at station D to the exclusion of the private line 29, 30 owing to the separation of the normal contacts at station D from the springs 16 and 17 thereat. In this way, as the invention is specifically embodied, either 20 station C or D may communicate with the other and either of these stations may have connection with the exchange by way of the party line to the exclusion of the other. On the other hand a calling station whose line 25 terminates at the exchange is totally excluded from the telephonic circuit that intervenes directly between the stations C, D by way of the private line 29, 30, a characteristic that is of importance particularly 30 where one of the stations C D is a called 35 station with respect to a line entering the exchange.

The element 18, in the preferred embodiment of the invention, is manually operated 40 through the manipulation of the associate telephone receiver which acts upon the element 18 through the intermediation of the receiver switch hook 13. I do not wish to be limited in all embodiments of my invention 45 to the switch hook control of the element 18.

While I have herein shown and particularly described the preferred embodiment of my invention I do not wish to be limited to 50 the precise details of construction and circuit arrangement illustrated, but

Having thus described my invention I claim as new and desire to secure by Letters Patent the following:—

55 1. A telephone exchange system including telephone lines extending from telephone substations to an exchange, one of said lines being a party telephone line extending from a plurality of party line stations to said 60 exchange; circuit connections whereby telephonic communication may be held between the party line stations to the exclusion of the exchange; switching mechanism for connecting the telephone at one of the party 65 line stations in telephonic circuit with the

party line and at that time serving to break the telephonic connection between the party line stations; and mechanism controlled by said switching mechanism serving to prevent the telephone at the party line station companion to that having said switching mechanism from becoming connected with the party line when the telephonic connection between the party line stations is broken. 70

2. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism for connecting the telephone at one of the party 80 line stations in telephonic circuit with the party line; and mechanism controlled by said switching mechanism serving to prevent the telephone at the remaining party line station from becoming connected with the party line, when said telephonic connection with the party line is established, and preserving such telephonic connection established between party line stations to the exclusion of the exchange. 85

3. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism for connecting the telephone at one of the party line stations in telephonic circuit with the party line; and mechanism serving to prevent the telephone at the remaining party line station from becoming connected with the party line, when said telephonic connection with the party line is established, and preserving such telephonic connection established between party line stations to the exclusion of the exchange. 90

4. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; means at the 105 110 115 120 125 130

station where this switching mechanism is located for preventing that operation of said switching mechanism that will permit the association of the associate telephone receiver with the party line; and means at the remaining party line station for governing the operation of the latter means.

5. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; means at the station where this switching mechanism is located for preventing that operation of said switching mechanism that will permit the association of the associate telephone receiver with the party line; and means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate telephone with the party line when said switching mechanism is free to effect this connection.

6. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; and means at the remaining party line station for governing the operation of the latter means.

7. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; and means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate telephone with the party line when said switching mechanism is free to effect this connection.

8. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; and means at the remaining party line station for governing the operation of the latter means, said electro-magnetic means having a bridge connection for including it across the party line; and a source of current in connection with the party line for energizing said electro-magnetic means when connected in bridge of the party line, the means for preventing the operation of said electro-magnetic means including a

bridge connection of the party line that contains the telephone thereat that serves to shunt sufficient current from said electro-magnetic means to prevent the operation thereof, the bridge including said electro-magnetic means being of sufficiently high resistance for the purpose.

9. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate telephone with the party line when said switching mechanism is free to effect this connection, said electro-magnetic means having a bridge connection for including it across the party line; and a source of current in connection with the party line for energizing said electro-magnetic means when connected in bridge of the party line, the means for preventing the operation of said electro-magnetic means including a bridge connection of the party line that contains the telephone thereat that serves to shunt sufficient current from said electro-magnetic means to prevent the operation thereof, the bridge including said electro-magnetic means being of sufficiently high resistance for the purpose.

10. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mech-

anism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means; and switching mechanism at the station where said electro-magnetic mechanism is located to enable the operation of said electro-magnetic mechanism to permit of the association of the associate receiver with the party line, this latter switching mechanism being so associated with said electro-magnetic mechanism as not to interfere with the control of said electro-magnetic mechanism exercised at the associate party line station.

11. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate telephone with the party line when said switching mechanism is free to effect this connection; and switching mechanism at the station where said electro-magnetic mechanism is located to enable the operation of said electro-magnetic mechanism to permit of the association of the associate re-

ceiver with the party telephone line, this latter switching mechanism being so associated with said electro-magnetic mechanism as not to interfere with the control of said 5 electro-magnetic mechanism exercised at the associate party line station.

12. A telephone exchange system including telephone lines extending from telephone substations to an exchange, one of said 10 lines being a party telephone line extending from a plurality of party line stations to said exchange; circuit connections whereby telephonic communication may be held between the party line stations to the 15 exclusion of the exchange; switching mechanism at one of the party line stations adapted in one condition of use to take part in establishing the telephonic connection between the party line stations that is independent of the exchange and in another condition of use to permit of the connection of the associate 20 telephone with the party line; electro-magnetic means at the station where this switching mechanism is located for preventing that operation of said switching mechanism that will permit the association of the associate telephone receiver with the party line; 25 means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate 30 telephone with the party line when said switching mechanism is free to effect this connection, said electro-magnetic means having a bridge connection for including it across the party line; a source of current in 35 connection with the party line for energizing said electro-magnetic means when connected in bridge of the party line, the means for preventing the operation of said electro-magnetic means including a bridge connection of the party line that contains the telephone thereat that serves to shunt sufficient current from said electro-magnetic means to prevent the operation thereof, the bridge including said electro-magnetic means being of sufficiently high resistance for the 40 purpose; and switching mechanism at the station where said electro-magnetic mechanism is located to enable the operation of said electro-magnetic mechanism to permit of the association of the associate receiver with the party telephone line, this latter switching mechanism being so associated with said electro-magnetic mechanism as not to interfere with the control of said electro-magnetic mechanism exercised at the 45 associate party line station.

50 13. A telephone exchange system including telephone lines extending from telephone substations to an exchange, one of said lines being a party telephone line extending from a plurality of party line stations to said exchange; circuit connections whereby telephonic communication may be held between the party line stations to the exclusion of the exchange; switching mechanism at one of the party line stations adapted in one 55 condition of use to take part in establishing

the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; 70 means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate 75 telephone with the party line when said switching mechanism is free to effect this connection, said electro-magnetic means having a bridge connection for including it across the party line; a source of current in 80 connection with the party line for energizing said electro-magnetic means when connected in bridge of the party line, the means for preventing the operation of said electro-magnetic means including a bridge connection of the party line that contains the telephone thereat that serves to shunt sufficient current from said electro-magnetic means to prevent the operation thereof, the bridge including said electro-magnetic means being of sufficiently high resistance for the 85 purpose; and switching mechanism at the station where said electro-magnetic mechanism is located to enable the operation of said electro-magnetic mechanism to permit of the association of the associate receiver with the party telephone line, this latter switching mechanism being so associated with said electro-magnetic mechanism as not to interfere with the control of said electro-magnetic mechanism exercised at the 90 associate party line station.

14. A telephone exchange system including telephone lines extending from telephone substations to an exchange where a common source of current is located, one of said lines being a party telephone line extending from a plurality of party line stations to said exchange; circuit connections whereby telephonic communication may be held between the party line stations to the exclusion of the exchange; switching mechanism for connecting the telephone at one of the party line stations in telephonic circuit with the party line and at that time 115 serving to break the telephonic connection between the party line stations; mechanism controlled by said switching mechanism serving to prevent the telephone at the party line station companion to that having 120

105

110

115

120

125

130

said switching mechanism from becoming connected with the party line when the telephonic connection between the party line stations is broken; means for preventing 5 operation at the exchange when telephonic communication is established between party line stations exclusively of the exchange; and means for removing the control of the latter means when telephonic connection is 10 established between the telephone at a party line station and the party line.

15. A telephone exchange system including telephone lines extending from telephone substations to an exchange where a 15 common source of current is located, one of said lines being a party telephone line extending from a plurality of party line stations to said exchange; circuit connections whereby telephonic communication 20 may be held between the party line stations to the exclusion of the exchange; switching mechanism for connecting the telephone at one of the party line stations in telephonic circuit with the party line; mechanism controlled by said switching mechanism serving 25 to prevent the telephone at the remaining party line station from becoming connected with the party line when said telephonic connection with the party line is established; means for preventing operation 30 at the exchange when telephonic communication is established between the party line stations exclusively of the exchange; and means for removing the control of the latter 35 means when telephonic connection is established between the telephone at a party line station and the party line.

16. A telephone exchange system including telephone lines extending from telephone substations to an exchange where a 40 common source of current is located, one of said lines being a party telephone line extending from a plurality of party line stations to said exchange; circuit connections 45 whereby telephonic communication may be held between the party line stations to the exclusion of the exchange; switching mechanism for connecting the telephone at one of the party line stations in telephonic circuit with the party line; mechanism serving 50 to prevent the telephone at the remaining party line station from becoming connected with the party line when said telephonic connection with the party line is established; 55 means for preventing operation at the exchange when telephonic communication is established between the party line stations exclusively of the exchange; and means for removing the control of the latter means 60 when telephonic connection is established between the telephone at a party line station and the party line.

17. A telephone exchange system including telephone lines extending from telephone substations to an exchange where a 65

common source of current is located, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; means at the station where this switching 70 mechanism is located for preventing that operation of said switching mechanism that will permit the association of the associate telephone receiver with the party line; means at the remaining party line station 75 for governing the operation of the latter means; means for preventing operation at the exchange when telephonic communication is established between the party line stations exclusively of the exchange; and means for removing the control of the latter means when telephonic connection is established between the telephone at a party line station and the party line.

18. A telephone exchange system including telephone lines extending from telephone substations to an exchange where a 80 common source of current is located, one of said lines being a party telephone line extending from a plurality of party line stations to said exchange; circuit connections whereby telephonic communication may be held between the party line stations to the exclusion of the exchange; switching mechanism at one of the party line stations 85 adapted in one condition of use to take part in establishing the telephonic connection between the party line stations that is independent of the exchange and in another condition of use to permit of the connection of the associate telephone with the party line; means at the station where this switching 90 mechanism is located for preventing that operation of said switching mechanism that will permit the association of the associate telephone receiver with the party line; means at the remaining party line station 95 for governing the operation of the latter means, there being a switch hook at the station where the aforesaid switching mechanism is located which serves to place said switching mechanism in condition to enable the establishment of telephonic connection 100 between the party line stations that is exclusive of the exchange and which switch hook 105 permits the connection of the associate telephone with the party line when said switching mechanism is free to effect this connection; means for preventing operation at the 110 exchange when telephonic communication is 115 established between the party line stations that is exclusive of the exchange and which switch hook 115 permits the connection of the associate telephone with the party line when said switching mechanism is free to effect this connection; means for preventing operation at the 120 exchange when telephonic communication is 125 established between the party line stations that is exclusive of the exchange and which switch hook 125 permits the connection of the associate telephone with the party line when said switching mechanism is free to effect this connection; means for preventing operation at the 130 exchange when telephonic communication is 130

established between the party line stations exclusively of the exchange; and means for removing the control of the latter means when telephonic connection is established between the telephone at a party line station and the party line.

19. A telephone exchange system including telephone lines extending from telephone substations to an exchange where a common source of current is located, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means; means for preventing operation at the exchange when telephonic communication is established between the party line stations exclusively of the exchange; and means for removing the control of the latter means when telephonic connection is established between the telephone at a party line station and the party line.

20. A telephone exchange system including telephone lines extending from telephone substations to an exchange where a common source of current is located, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means, there being a switch hook at the station where the aforesaid switching mechanism is located which serves to place

said switching mechanism in condition to enable the establishment of telephonic connection between the party line stations that is exclusive of the exchange and which switch hook permits the connection of the associate telephone with the party line when said switching mechanism is free to effect this connection; means for preventing operation at the exchange when telephonic communication is established between the party line stations exclusively of the exchange; and means for removing the control of the latter means when telephonic connection is established between the telephone at a party line station and the party line.

21. A telephone exchange system including telephone lines extending from telephone substations to an exchange where a common source of current is located, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means, said electro-magnetic means having a bridge connection for including it across the party line; a source of current in connection with the party line for energizing said electro-magnetic means when connected in bridge of the party line, the means for preventing the operation of said electro-magnetic means including a bridge connection of the party line that contains the telephone thereat that serves to shunt sufficient current from said electro-magnetic means to prevent the operation thereof, the bridge including said electro-magnetic means being of sufficiently high resistance for the purpose; means for preventing operation at the exchange when telephonic communication is established between the party line stations exclusively of the exchange; and means for removing the control of the latter means when telephonic connection is established between the telephone at a party line station and the party line.

22. A telephone exchange system including telephone lines extending from telephone substations to an exchange where a common source of current is located, one of

said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate telephone with the party line when said switching mechanism is free to effect this connection, said electro-magnetic means having a bridge connection for including it across the party line; a source of current in connection with the party line for energizing said electro-magnetic means when connected in bridge of the party line, the means for preventing the operation of said electro-magnetic means including a bridge connection of the party line that contains the telephone thereat that serves to shunt sufficient current from said electro-magnetic means to prevent the operation thereof, the bridge including said electro-magnetic means being of sufficiently high resistance for the purpose; means for preventing operation at the exchange when telephonic communication is established between the party line stations exclusively of the exchange; and means for removing the control of the latter means when telephonic connection is established between the telephone at a party line station and the party line.

23. A telephone exchange system including telephone lines extending from telephone substations to an exchange where a common source of current is located, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate telephone with the party line when said switching mechanism is free to effect

establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means; switching mechanism at the station where said electro-magnetic mechanism is located to enable the operation of said electro-magnetic mechanism to permit of the association of the associate receiver with the party telephone line, this latter switching mechanism being so associated with said electro-magnetic mechanism as not to interfere with the control of said electro-magnetic mechanism exercised at the associate party line station; means for preventing operation at the exchange when telephonic communication is established between the party line stations exclusively of the exchange; and means for removing the control of the latter means when telephonic connection is established between the telephone at a party line station and the party line.

24. A telephone exchange system including telephone lines extending from telephone substations to an exchange where a common source of current is located, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate telephone with the party line when said switching mechanism is free to effect

this connection; switching mechanism at the station where said electro-magnetic mechanism is located to enable the operation of said electro-magnetic mechanism to permit 5 of the association of the associate receiver with the party telephone line, this latter switching mechanism being so associated with said electro-magnetic mechanism as not to interfere with the control of said 10 electro-magnetic mechanism exercised at the associate party line station; means for preventing operation at the exchange when telephonic communication is established between the party line stations exclusively of 15 the exchange; and means for removing the control of the latter means when telephonic connection is established between the telephone at a party line station and the party line.

20 25. A telephone exchange system including telephone lines extending from telephone substations to an exchange where a common source of current is located, one of said lines being a party telephone line extending from a plurality of party line stations to said exchange; circuit connections whereby telephonic communication may be held between the party line stations to the exclusion of the exchange; switching mechanism 25 at one of the party line stations adapted in one condition of use to take part in establishing the telephonic connection between the party line stations that is independent of the exchange and in another condition of use to permit of the connection of 30 the associate telephone with the party line; electro-magnetic means at the station where this switching mechanism is located for preventing that operation of said switching mechanism that will permit the association 35 of the associate telephone receiver with the party line; means at the remaining party line station for governing the operation of the latter means, said electro-magnetic 40 means having a bridge connection for including it across the party line; a source of current in connection with the party line for energizing said electro-magnetic means when connected in bridge of the party line, 45 the means for preventing the operation of said electro-magnetic means including a bridge connection of the party line that contains the telephone thereat that serves to shunt sufficient current from said electro- 50 magnetic means to prevent the operation thereof, the bridge including said electro-magnetic means being of sufficiently high resistance for the purpose; switching mechanism at the station where said electro-magnetic 55 mechanism is located to enable the operation of said electro-magnetic mechanism to permit of the association of the associate receiver with the party telephone line, this latter switching mechanism being so associated with said electro-magnetic mecha-

nism as not to interfere with the control of said electro-magnetic mechanism exercised at the associate party line station; means for preventing operation at the exchange when telephonic communication is established between the party line stations exclusively of the exchange; and means for removing the control of the latter means when telephonic connection is established between the telephone at a party line station and the party line.

26. A telephone exchange system including telephone lines extending from telephone substations to an exchange where a common source of current is located, one of said lines being a party telephone line extending from a plurality of party line stations to said exchange; circuit connections whereby telephonic communication may be held between the party line stations to the exclusion of the exchange; switching mechanism at one of the party line stations adapted in one condition of use to take part in establishing the telephonic connection between the party line stations that is independent of the exchange and in another condition of use to permit of the connection of the associate telephone with the party line; electro-magnetic means at the station where this switching mechanism is located for preventing that operation of said switching mechanism that will permit the association of the associate telephone receiver with the party line; means at the remaining party line station for governing the operation of the latter means, there being a switch hook at the station where the aforesaid switching mechanism is located which serves to place said switching mechanism in condition to enable the establishment of telephonic connection between the party line stations that is exclusive of the exchange and which switch hook permits the connection of the associate telephone with the party line when said switching mechanism is free to effect this connection, said electro-magnetic means having a bridge connection for including it across the party line; a source of current in connection with the party line for energizing said electro-magnetic means when connected in bridge of the party line, the means for preventing the operation of said electro-magnetic means including a bridge connection of the party line that contains the telephone thereat that serves to shunt sufficient current from said electro-magnetic means to prevent the operation thereof, the bridge including said electro-magnetic means being of sufficiently high resistance for the purpose; switching mechanism at the station where said electro-magnetic mechanism is located to enable the operation of said electro-magnetic mechanism to permit of the association of the associate receiver with the party telephone line.

line, this latter switching mechanism being so associated with said electro-magnetic mechanism as not to interfere with the control of said electro-magnetic mechanism exercised at the associate party line station; means for preventing operation at the exchange when telephonic communication is established between the party line stations exclusively of the exchange; and means for removing the control of the latter means

when telephonic connection is established between the telephone at a party line station and the party line.

In witness whereof, I hereunto subscribe my name this 24th day of July A. D., 1911.

MORTON L. JOHNSON.
